UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,364.

Specification for Design.

Patented July 11, 1916.

Application filed March 28, 1916. Serial No. 87,367. Term of patent 3½ years.

To all whom it may concern:

Be it known that I, JOHN S. MONAGHAN, a citizen of the United States, and a resident of the city of Rochester, county of Monroe, State of New York, have invented a new, original, and ornamental Design for Buttons, of which the following is a specification.

My design is represented in the accompanying drawing in which:

Figure 1 is a plan view of a button showing my new design. Fig. 2 is a side elevation. Fig. 3 is a vertical section on a horizontal line drawn through Fig. 1.

The article is octagonal in shape having a circular depression in its center. The upper surface of the button is roughened between two concentric circles, the edge beyond the

outer circle being smooth as well as the surface of the central depression. One half of the face of the button and the curved portion at the center are of uniform color, the other half of the face of the button is provided with horizontal lines of contrasting colors.

I claim:

The ornamental design for a button substantially as shown and described.

In witness whereof I have hereunto set my hand at Rochester, in the county of Monroe and State of New York, this 24th day of March, 1916.

JOHN S. MONAGHAN.

In presence of—

EARL A. WELLER,
GERTRUDE M. HILLER.
